UNITED STATES PATENT OFFICE.

ROBERT S. HURLEY, OF CLEVES, OHIO.

APPARATUS FOR HANDLING RAILWAY TIES.

Application filed October 18, 1920. Serial No. 417,708.

To all whom it may concern:

Be it known that I, ROBERT S. HURLEY, a citizen of the United States, residing at Cleves, in the county of Hamilton and State 5 of Ohio, have invented certain new and useful Improvements in Apparatus for Handling Railway Ties, of which the following is a specification.

This invention relates to an apparatus for 10 handling railway ties, and has for its more specific object to provide a simple and efficient apparatus to pick up ties which are piled in ricks for seasoning in a storage field and transfer and load them into small narrow gauge trams holding about thirty ties each, which trams are then run into treating cylinders in trains of fifteen at a time, wherein the ties are impregnated with creosote. The tie ricks are about 12 feet high 15 and forty feet long containing five stacks each. Opposite one end of the ricks are standard gauge tracks on which the ties are brought into the storage field, and opposite the other end of the ricks are the tram 20 tracks; these tracks dividing the field into narrow yards.

The apparatus of the present invention is 25 designed to facilitate and expedite the loading of the ties from the ricks onto the tram cars.

In the accompanying drawings I have illustrated a practical and approved embodiment of my invention, and referring thereto:

30 Fig. 1 is a side elevation of a rick comprising five stacks arranged in a row, a tram track lying opposite one end of the rick and my improved transfer apparatus applied thereto;

Fig. 2 is a top plan view of the parts 40 shown in Fig. 1;

Fig. 3 is a view similar to Fig. 1 illustrating a different position of the trolley line and a somewhat different transfer and loading apparatus which is brought into use when the rick, in the unloading of the same, has been lowered to a point at which the use 45 of the tram loading boom is unnecessary;

Fig. 4 is a top plan view of the parts 50 shown in Fig. 3;

Figs. 5, 6, 7 and 8 are detail views of the tie carrier and transfer hook, Fig. 5 showing a side elevation in the carrying position, Fig. 6 a front elevation as viewed from the 55 right of Fig. 5, Fig. 7 a side elevation in the

dumping or discharging position and Fig. 8 a transverse section on the line 8-8 of Fig. 5;

Fig. 9 is a side elevation, and Fig. 10 an end elevation, of an improved trolley more 60 especially adapted for use in that phase of the work illustrated in Figs. 3 and 4;

Fig. 11 is a side elevation and Fig. 12 a top plan of the brake controlled lead lowering device employed on the loading boom; 65

Figs. 13 and 14 are elevational views taken in planes of right angles to each other of a device in the nature of a jack for lifting the trolley cable and trolley after the tie-carrier has received its load from the rick 70 and facilitating its travel from the rick to the loading boom;

Figs. 15 and 16 are side elevation and top plan views, respectively, of a swivel roller construction designed to facilitate the 75 transfer of individual ties from the trolley directly onto the tram car;

Figs. 17, 18 and 19 are detail views of an improved differential pulley block-and-tackle; Fig. 17 being a perspective elevation, 80 broken out between its ends, Fig. 18 being a horizontal axial section, and Fig. 19 being a detail of the clutch shifting sleeve and cam;

Figs. 20, 21 and 22 are views of an expander for elevating one end of the top row 85 of ties on a stack to facilitate the insertion thereunder of the tie carrier; Fig. 20 being a plan and Figs. 21 and 22 being end views in folded and open positions respectively; 90 and

Figs. 23 and 24 are enlarged elevations, at 95 right angles to each other, of a stack of ties illustrating the method of piling the latter in the stack.

Referring to the drawings R designates as an entirety a rick of ties consisting, as is common practice, of a group of stacks s^1 , s^2 , s^3 , s^4 , piled side by side in a single row. T designates a narrow gauge tram track running past one end of the rick, and C designates as an entirety a tram car on which the ties are loaded and then carried into the treating cylinders. 100

Located adjacent to the track T and centrally opposite one end of the tie rick R is a round mast 20 having an upper section 20' vertically swiveled thereon by means of a bearing sleeve or ferrule 20^a supported by a collar 20^b and cotter pin 20^c; said upper 105

swiveled mast section 20' carrying a horizontal transfer arm 21 adapted to swing over the track. Extending over and supported upon the top of the mast 20 and above and 5 lengthwise of the rick R is a trolley cable 22, the other end of which is supported upon a strut 23 footed upon the rick, the end of the cable being suitably anchored to the ground at 24, or to the bottom tie.

10 Mounted to travel on the trolley cable 22 is a trolley 25 from which is suspended a pulley block-and-tackle indicated at 26, this latter having suspended therefrom a transfer hook designated as an entirety by 27, and 15 more particularly described hereinafter as to its peculiar construction and mode of manipulation. Hung from the transfer hook 27 is the tie-carrier 28. Suspended from the transfer arm 21 is an endless chain 77 20 controlled by a brake designated generally by 30, this chain being designed to receive the loaded tie-carrier 28 and transfer hook 27 from the trolley 25 and lower the tie-carrier to proper dumping position over 25 either of a pair of tram cars C, standing adjacent to the mast 20.

31 designates as an entirety a hand operated jack which is footed on the rick R and 30 liftingly engages the cable 22 adjacent to the loading point of the trolley carrier. There is, of course, some slack and dip in the cable 22; and the purpose of this cable lifting device is to elevate the loaded trolley and the 35 cable after the tie-carrier has been engaged with a load of ties and its weight partly transferred to the cable by the hoist, and start it on its way by gravity toward the unloading apparatus.

40 The operation of the apparatus as a whole will perhaps be better understood following upon a more specific and detailed description of the several devices already generally described.

45 Referring to Figs. 5 to 8 inclusive, in which I have illustrated in detail the structure of the tie-carrier, this member comprises a pair of parallel cantilever arms each consisting of a horizontal tie-carrier bar 32 and an upwardly inclined suspension bar 33. 50 The suspension bars 33 are connected at their upper ends by a transverse rod 34, and the tie-carrier arms 32 are similarly connected by a transverse rod 35, thereby providing a frame-like construction. Pivoted to the inner sides of the bar 33 at 36 are a pair of suspension links 37, and extending through and between the lower ends of the links 37 is a rod 38 having on one end an operating handle 39 bent at right angles thereto and 60 on its other end a short toggle arm 40. Rigidly fastened to the outer sides of the arms 33 are a pair of toggle arms 41. One of the toggle arms 41 is pivoted to the handle 39 at 42, and the other toggle arm 41 is similarly pivoted to the arm 40 at 43. Each of

the arms 41 has, beyond its pivot, an extension 41' which forms a stop to limit the expanding movement of the toggle.

Secured to the rod 38 which, it will be remembered, pivotally connects the lower ends 70 of the links 37, is a rope or cable 44, constituting a bail, this cable passing through a sleeve 45' mounted in the lower end of a pulley block 45, which block carries a pulley 46 mounted to ride on the transfer hook 27. 75 The bail 44 may be slipped through the sleeve 45' several inches either way to more perfectly balance the load if too heavy on one end.

80 In the position of the parts shown in Figs. 5 and 6, which is the lowering, lifting and carrying position of the device, the suspension axis 36 of the carrier frame is directly above and in vertical line with its center of gravity. When, however, the handle 39 is swung upwardly to substantially the position shown in Fig. 7, the toggle is broken, and the point of suspension is shifted rearwardly from the suspension axis 36, 85 thereby causing the bottom bars 32 of the carrier frame to assume the tilted position shown in Fig. 7 so that the ties readily slide off onto the tram car. When the handle 39 is returned to the position shown in Fig. 5, the point of suspension is shifted back to the pivot axis 36, and the bottom bars 32 assume the horizontal position.

90 The transfer hook 27 consists of a rod bent into triangular form as more clearly shown in Figs. 5 and 7 and having a lower pulley engaging member 27', and a pair of upwardly and inwardly inclined arms 27^a and 27^b. The arm 27^a terminates in an outwardly bent hook 27^c, and the other arm 27^b has a hook 27^d that terminates in an outwardly extending operating arm or handle 27^e. When the tie-carrier is connected to the trolley through the intervention of this transfer hook 27, as shown in Figs. 1 and 5, the transfer hook takes the relative position 100 shown in Fig. 5, the transfer hook 27 being suspended from the hook 26' of the block-and-tackle 26 by the hook 27^d.

105 In Figs. 9 and 10 I have illustrated the details of a cable trolley such as is preferably used for transporting the ties from the rick to the transfer and distributing arm. This trolley comprises a wheeled truck consisting of parallel side beams 47, a pair of axles 48 and a pair of grooved trolley wheels 49, mounted on the axles 48 and traveling on the cable 22. Suspended from the side beams 47 is a U-shaped hanger frame 52, carrying a grooved pulley 53 on which is hung the cable 26, (Figs. 1 and 3). In order to hold the trolley in loading and unloading position on the cable, there are pivoted on the axles 48 a pair of dogs 54 formed with V-shaped notches 55 at their lower ends which bite 115 the cable under the influence of a pull 120

spring 56, connecting the two dogs. On the upper ends of the dogs 54 are inwardly extending arms 57 the free ends of which lap over and are slotted to receive the notched 5 end of a pull cord 58. When the trolley is ready to travel from the rick to the tram, or in the reverse direction, the operator pulls down on the cord 58, thereby releasing the dogs 54 from the cable, and then pushes or 10 pulls the loaded or empty trolley to its destination.

To the lower end of the hanger frame 52 is pivoted a block 59 having a transverse hole 60 to receive a pole 61 adjustably secured 15 thereon by a set screw 62. This pole 61 is more particularly hereinafter described in connection with the second phase of the loading operation represented in Figs. 3 and 4.

20 Figs. 11 and 12 illustrate the details of a load lowering mechanism that is mounted on the transfer and distributing arm 21. Where this arm is of sufficient length to overhang two adjacent tram cars standing in 25 load receiving position, this lowering mechanism may be stationary on the arm; but in some cases the ties, which are classified according to quality, and separated into different trams, are classified in three divisions, instead of only two, thus requiring 30 three cars at the load receiving point. To accommodate a three-fold division or classification, the load lowering mechanism is preferably mounted to travel on a trackway 35 63 on the transfer and distributing arm, and comprises a truck consisting of a pair of parallel beams 64 and 65 mounted on axles 66, these latter supported on wheels 67 traveling on the trackway.

40 Fast on the rear axle 66 is a grooved pulley 68 and the brake 30, comprising a brake disc 69, encircled by a brake band 70. One end of the brake band 70 is attached at 71 to the truck beams 64 and 65, and its other 45 end is attached at 72 to a lever arm 73 that is pivoted at one end on the axle 66. The arm 73 is connected to the truck beams 64 and 65 by a pull spring 74 thus normally applying the brake band to the brake disc.

50 Journalized between the truck beams 64 and 65 at one side of the grooved pulley 68 is an idler grooved pulley 75; and on the axle 66 at the outer end of the transfer arm is a third groove pulley 76. Over the pulleys 55 68 and 76 and beneath the idler pulley 75 is trained an endless chain 77 that hangs down in the form of a loop, as clearly shown in Fig. 1. To the free end of the lever arm 73 is attached a depending pull cord 78.

60 In Figs. 13 and 14 is shown a form of cable hoist or jack which is preferably used for lifting the sagged cable and the loaded tie-carrier preliminary to transmitting the load from the rick to the tram.

65 79 designates a post, which may be a round

or square section of tubing, the lower end of which is footed directly upon the top of the stack from which the ties are being taken. Slidably mounted on the post 79 is a strap 80 carrying a U-shaped hanger 81 in which is 70 journaled a grooved sheave 82 that directly engages with the cable 22. To the shaft of the sheave is connected a clevis 83 a smaller clevis 85 having a contracted upper end that receives the lower end of a rope 86. The 75 rope 86 passes over a sheave 87 journaled in the upper end of the post 79 and at its lower end is connected by a clevis 88 to a hand lever 89. This hand lever has pivoted thereto at 90 and 91 a pair of depending strips 80 92 and 93, respectively, to the lower end of which strips are secured laterally extending collars 94 and 95 that embrace the post 79. As the hand lever 89 is swung up and down the pivots 90 and 91 alternately become the 85 fulcrums of the lever, the collars 94 and 95 gradually moving downwardly on the post 79 and alternately gripping the edges of the post as they assume canted positions on the latter. As the hand lever is then swung 90 downwardly, the collar 95 in turn is canted to grip the post and the collar 94 slides downwardly a slight distance. In this way as the hand lever is swung up and down, the end of the rope 86 attached to the hand 95 lever is drawn downwardly, and the sheave 82 and cable 22 are correspondingly elevated. The tie-carrier with its load is thus lifted clear of the stack leaving the trolley free to slide or be pushed to the tram loading boom. As the stack is lowered, the jack may be lengthened by having an extension length screwed into its lower end.

100 Figs. 15 and 16 illustrate a construction of 105 swivel roller that is used on the trams during what I term the second phase of the loading operation illustrated in Figs. 3 and 4. The tram car has on each side a pair of curved upstanding posts 96 in the upper ends of which are sockets 97 (Fig. 15). 98 110 designates a flat bar formed at its ends with depending tenons 99 that fit into the sockets 97 on one side of the tram car, the bar 98 thus bridging the space between the two posts 96 on that side of the car. In the bar 98 are a plurality of holes 100, in any of which is mounted a vertically adjustable spindle 101 carrying at its upper end a yoke 102. Journalized in the upstanding arms of the yoke 102 is a roller 103, the longitudinal 115 axis of which is preferably slightly inclined to the bar 98. The yoke 102 at the lower end of the roller 103 has a pair of upstanding arms 104 on the upper ends of which are 120 journaled substantially vertical rollers 105. The function and mode of use of this device is hereinafter explained in the description of the operation of the complete system.

125 For raising and lowering the tie-carrier any 130

known and suitable block-and-tackle may be employed within the broad purview of the invention; but in Figs. 17, 18, and 19 I have illustrated a construction of differential 5 block-and-tackle designed to effect the rapid lowering and raising of the tie-carrier in situations permitting such rapid operations.

Referring to these views, 106 designates as an entirety the frame of the upper pulley 10 block, in which are journaled on a shaft 107 a pair of differential pulleys 108 and 109. 15 110 designates the frame of the lower block, in which is journaled on a shaft 111 a single pulley 112. The chain 113 is an endless 20 chain which has a geared engagement with the several pulleys, the peripheries of the latter being formed with pockets 114 that fit the links of the chain. As shown in Fig. 17, 25 one limb 113^a of the hand pull section of the chain extends upwardly over the larger pulley 108. Thence the chain extends downwardly and around the lower half of the pulley 112, thence upwardly and over the smaller pulley 109, thence downwardly 30 forming the other limb 113' of the hand pull section connected by a depending loop with the hand pull section 113^a. In the ordinary differential block-and-tackle the two pulleys in the upper block are integral or rigidly 35 connected and always turn simultaneously in the same direction. Further describing my present improvement, the pulleys 108 and 109 are independently journaled on the shaft 107. The pulley 108 has a conical 40 socket 114' adapted to receive a conical boss 115 on the adjacent face of the pulley 109, thereby forming a cone friction clutch. Preferably also the other face of the pulley 109 is formed with a conical socket 116 designed to co-operate with a conical annular 45 rim or boss 117 on one side member of the frame 106.

Slidably mounted on the shaft 107 to the right of pulley 109 (Fig. 18) is a sleeve 118 formed with a longitudinal slot 119 entered by a pin 120 in the frame 106, whereby said sleeve is permitted a limited longitudinal movement but is locked against rotation. 50 On the inner end of sleeve 118 is a radial flange 121 confined within an annular keeper ring 122 on the side of pulley 109. Fast on the outer end of sleeve 118 is a disc 123 formed on its inner face with a series of cam teeth 124. Loosely mounted on the sleeve 118 55 between the outer side of the frame and the cam disc 123 is a similar disc or ring 125 formed on its outer face with cam teeth 126 similar and opposed to the cam teeth 124. Preferably the outer ends of the teeth 124 60 are flattened, as shown at 124', and similarly the outer ends of the cam teeth 126 are flattened as shown at 126'. Integral or rigid with the cam disc 125 are radially extending arms 127 and 128 equipped with depending 65 pull cords 129 and 130, respectively. Be-

tween the flange 121 of the sleeve 118 and the opposite side of the frame is interposed a powerful compression spring 131.

In the operation of this block-and-tackle, when the loaded tie-carrier is to be elevated, 70 the cam disc 125 is in a position such that its teeth fully interfit with the teeth of the cam disc 123, whereby the cone 115 is formed into clutch engagement with the socket 114', so that the two pulleys are locked to rotate 75 in unison.

By pulling down upon the section 113^a of the chain, the slack of the cable is taken up sufficiently to permit the jack to accomplish the actual lifting of the carrier and load 80 free of the pile. In order to quickly lower the empty carrier at the stack it is necessary only to turn the cam disc 125 slightly by pulling downwardly on the cord 129. This, 85 through the sleeve 118, disconnects the smaller pulley 109 from the larger pulley 108, thus permitting the two pulleys to rotate simultaneously in opposite directions, thereby effecting the rapid descent of the tie-carrier, the descent being regulated by 90 the partial contact of the clutch members acting as a brake. This descent is arrested at the desired point by a quick pull on the cord 130 which instantly brings, through the spring 131, the two pulleys into fully coupled engagement with each other. For lifting light loads, where the full mechanical advantage of the differential pulleys is not required, the cam disc 125 may be turned 95 slightly further until the flat sides of the teeth lie against each other. When this occurs the pulley 109 is brought into clutch engagement with the fixed boss 117 on the frame, whereby said pulley is locked to the 100 frame. The section of the chain passing over the smaller pulley 109 is thus, in effect, locked to the frame and the construction is reduced to a simple block-and-tackle, having 105 one movable pulley 108. Again, by placing the pulley 109 in the intermediate position, the empty tie-carrier can be quickly elevated by pulling down on both hand pull sections 110 113^a of the chain.

Railway ties when brought into the yard 115 are piled in the manner illustrated in Figs. 23 and 24. First, a pair of ties "a" are laid on the ground in parallel relation and a tie length apart. Then a horizontal row "b" of ties is laid upon them. Then the single tie "c" is laid crosswise of one end of the horizontal row "b". Then an inclined row "d" is laid, resting at one end on the tie "c" and at the opposite end on the row "b". Then a transverse tie "e" is laid across the lower end of the row "d", and the horizontal row "f" 120 rests at one end on the tie "e" and at the other end on the high end of the row "d", and so on.

To properly enter the lifting arms of the tie-carrier beneath several ties, it is usually 125 130

necessary to more or less raise that end of the top row which rests directly upon the next underlying row. To facilitate this, I have designed a simple and effective lifter 5 or expander which is shown in detail in Figs. 20, 21 and 22. This device comprises simply a pair of thin flat bars 132 and 133 which are pivotally united at one longitudinal edge by hinges 134. Connected to or integral with the bars 132 and 133 are laterally extending handles 135 and 136, respectively. The bars 132 and 133 in folded position are inserted between the top row and the next underlying row of ties, and the handles 135 10 and 136 are tilted upwardly or downwardly, as illustrated in Fig. 22, which opens the two bars of the expander, thereby raising the top row sufficiently to enable the arms of the tie-carrier to be readily inserted therebelow. 15

After the rick has been reduced in height to a point where it is unnecessary to use the transfer and distributing arm 21 and its tie-carrier lowering mechanism, the overhead 20 cable 22 is lowered and suitably tensioned, as shown in Figs. 3 and 4, the cable at the tram loading point being conveniently supported on a pin or stud 137 in the mast 20.

At this point or phase of the operation, the 25 twin arm tie-carrier illustrated in detail in Figs. 5 to 8 inclusive may conveniently be replaced by a single arm carrier consisting of a simple hook member 138 having a foot 139 of a size to engage beneath and lift a 30 single tie. Co-operating with the hook 138 is a tie supporting and steadyng device having the general form of an ordinary boat-hook and consisting of the pole 61 hereinbefore referred to in the description of the 35 trolley (Figs. 9 and 10), the lower end of this pole having a pointed spike 140 adapted to radially pierce the end of a tie, and the pole being further equipped with a handle 141 by which the tooth may be forced into or 40 pulled out of the end of the tie.

As previously described, the upper end of the pole 61 is adjustably mounted in the swivel block 59 so that the pole can be shortened or lengthened and acts to assume 45 any angle in a vertical plane necessary to effect the registration of the tooth 140 with the end of a tie. When using this tie-carrier, the lower end or foot 139 is entered beneath a single tie slightly to one side of 50 the center of the latter. The spike 140 of the steadyng pole 61 is then jammed into the longer or heavier end of the tie, the cable jack is then manipulated to elevate 55 the cable, and the loaded trolley is then pushed or pulled to a point alongside the tram car. The end of the tie engaged by 60 the hook is then swung until it rests upon one of the rollers 103 of the tram car, this 65 position of the tie being indicated by dotted lines in Fig. 3. The operator then lifts

the other end of the tie until it is free of the tie-carrier, pushes the tie forwardly on the roller, and simultaneously thrusts the tie laterally off the roller and onto the tram car. This method of transferring the ties 70 is more speedy and efficient than the method delineated in Figs. 1 and 2 after the rick or stack has been lowered to a point at which the cable assumes an up-slant from the stack or rick to the mast, since reducing 75 the power necessary to move the loaded trolley along the cable, and dispensing with the transfer and lowering mechanism between the trolley and the tram car. Of course, the same twin arm tie-carrier previously described might be used at this point 80 or phase of the operation, if desired, but the simple single arm carrier with co-operating steadyng hook conduces more efficiently to the manual up-ending of the tie 85 on the swivel roller and the rolling of the tie off onto the tram.

The operation of the apparatus has been to a considerable extent indicated in connection with the description of its various 90 co-operating parts and elements, but may briefly be outlined as follows:

The cable having been properly spaced and tensioned above the rick and mast, the trolley having the twin arm tie-carrier suspended therefrom by the transfer hook as shown in Fig. 1, is pushed or drawn to a position over one of the stacks or ricks, and the lifting arms of the carrier are entered beneath three or more ties in the top 95 row of a stack, the expander being entered beneath the top row and manipulated, if necessary, to sufficiently separate the top row from the next underlying row to permit of the insertion of the carrier. The 100 hoist is next manipulated to transfer a part of the weight of the load to the cable, bowing the latter downwardly to some extent. The jack is then stepped on the top of the stack closely adjacent to the trolley, 105 and is manipulated to raise the cable and the loaded trolley. For the most part, this will effect a down-slant of the cable so that the trolley will travel to the unloading and distributing point by gravity, but if not, 110 the trolley is positively moved by manual or power pushing or pulling until it is alongside the unloading mechanism on the transfer arm 21. The hook 27^c of the transfer hook is then slipped over one link of 115 the chain 29 and between the two adjacent links, and the arm 27^e is then lifted off the hook 26^c of the block-and-tackle. This causes the roller 46 to run down to the opposite angle of the transfer hook, 120 whereby the trolley is freed of the load and the latter is suspended by the chain 77 and swung above the tram car provided for the particular class of ties it carries. A down pull on the cord 78 permits the loaded 125 130

carrier to descend by gravity to the bottom of the loop formed by the chain 77, whereupon by throwing the handle 39 of the carrier from the position shown in Fig. 5 to that shown in Fig. 7, the carrier frame is tilted and the ties slide by gravity down onto the tram car. By manual manipulation of chain 77 the empty carrier is then raised to the proper height on the rear limb 10 of chain 77 where it waits until the carrier with its next load is deposited on the front limb of chain 77 when it is transferred to the trolley. In effecting such transfer to the trolley the bent end 27^d of the transfer 15 hook is engaged with the hook 26' of the block-and-tackle, whereupon, by swinging the arm 27^e downwardly the empty carrier slides back to the position shown in Fig. 5 whereupon the empty carrier is returned by the trolley to a position above the stack 20 ready to receive another load. Of course, where two or more cars are in waiting position, the transfer arm 21 is swung to one side or the other to a position over the 25 car which receives the ties, the mechanism traveling inwardly or outwardly on the transfer arm as may be necessary to secure the proper unloading position. This selective feature is of importance because permitting a grouping or separation of the ties, 30 according to quality, onto two or three tram cars in waiting position.

After the rick has been unloaded substantially to or beyond the point indicated 35 in Fig. 3, the simpler single arm tie-carrier is preferably substituted, the trolley cable is lowered, the swivel roller attachments are applied to the tram cars, and the further or second phase loading proceeds in a manner already described until the last ties of 40 the rick or stack have been transported and loaded onto the cars.

So far as I am aware, my present invention represents the first effort in the direction of mechanical loading and selective distributing of railway ties from the ricks or 45 stacks onto the tram cars used in the creosoting process. To my knowledge, this work has been done by hand for the past sixty years or more. The direct and intimate manner in which the several elements of the complete apparatus co-operate to bring about the unitary result of the rapid 50 loading and grading of the ties will be evident to all persons at all familiar with this particular industry. Manifestly, so far as the complete apparatus is concerned, the individual parts or elements may be variously modified and changed from those herein 55 specifically shown and described, and hence, in the broader claims I do not wish to be understood as restricting the several elements recited therein to the particular mechanical forms or embodiments herein shown 60 and described as preferably employed.

I claim:

1. In an apparatus for transferring railway ties from a stack to a tram car, the combination of a trolley cable disposed above the stack and extending thence to 70 a point adjacent to the car, a trolley mounted to travel on said cable, a tie-carrier suspended from said trolley, and a jack adapted to liftingly engage with the cable at a point adjacent to the loaded tie-carrier. 75

2. In an apparatus for transferring railway ties from a stack to tram cars, the combination of a mast located adjacent to said cars, a horizontally swinging transfer arm on said mast movable to positions overhanging said cars, a load-lowering device mounted on said transfer-arm, a trolley cable disposed above the stack and extending thence to said mast, a trolley mounted to travel on said cable, and a tie-carrier suspended from said trolley. 85

3. In an apparatus for transferring railway ties from a stack to tram cars, the combination of a mast located adjacent to said cars, a horizontally swinging transfer-arm 90 on said mast movable to positions overhanging said cars, a load-lowering device mounted on said transfer arm, a trolley cable disposed above the stack and extending thence to said mast, a trolley mounted to travel on said cable, a tie-carrier suspended from said trolley, and a jack adapted to liftingly engage with said cable at a point adjacent to the loaded tie-carrier. 95

4. In an apparatus for transferring railway ties from a stack to tram cars, the combination of a mast located adjacent to said cars, a horizontally swinging transfer arm on said mast movable to positions overhanging said cars, a load-lowering mechanism, including a depending chain, mounted on said transfer arm, a trolley cable disposed above the stack and extending thence to said mast, a trolley mounted to travel on said cable, a block-and-tackle suspended from said 110 trolley, a tie-carrier, and a transfer member from which said tie-carrier is hung, said transfer member being alternately engaged with said block-and-tackle and said chain. 115

5. In an apparatus for transferring railway ties from a stack to tram cars, the combination of a mast located adjacent to said cars, a horizontally swinging transfer-arm 120 on said mast movable to positions overhanging said cars, a load-lowering mechanism, including a depending endless chain and a chain supporting and controlling mechanism mounted to travel on said transfer arm, a trolley cable disposed above the stack and extending thence to said mast, a trolley mounted to travel on said cable, a block-and-tackle suspended from said trolley, a tie carrier, and a transfer hook on 125 which said tie-carrier is suspended, said 130

transfer-hook being alternately engaged with said block-and-tackle and said chain.

6. In an apparatus for transferring railway ties from a stack to tram cars, the combination of a mast located adjacent to said cars, a horizontally swinging transfer arm on said mast movable to positions overhanging said cars, a load-lowering mechanism, including a depending endless chain,

10 and a chain supporting and controlling mechanism, mounted to travel on said transfer arm, a trolley cable disposed above the stack and extending thence to said mast, a trolley mounted to travel on said cable, a block-and-tackle, suspended from said trolley, a tie-carrier, a transfer hook having a portion permanently engaged with said tie-carrier and separated portions alternately engageable with said block-and-tackle and

20 said chain, and a jack adapted to liftingly engage with said cable at a point adjacent to the loaded tie-carrier.

7. In an apparatus for transferring railway ties, the combination of a transfer arm disposed above a tram car, a pair of spaced pulleys mounted on said arm, an endless load-receiving chain suspended from said pulleys, a brake disc fast with one of said pulleys, a spring-tensioned brake-band encircling said brake disc, and a manually operable lever for expanding said brake-band.

8. In an apparatus for transferring railway ties, the combination of a mast, a horizontally swinging transfer arm on said mast,

and formed with a track-way, a truck movable on said track-way, a pair of spaced pulleys journaled on said truck, an endless load-receiving chain suspended from said pulleys, a brake-disc fast with one of said pulleys, a spring-tensioned brake-band encircling said brake-disc, and a manually operable lever for expanding said brake-band.

9. In a transfer apparatus for railway ties, a transfer device for shifting a tie-carrier between a trolley hook and a load-lowering chain consisting of a substantially triangular member having a base portion on which the tie-carrier is slidably suspended and upwardly and inwardly inclined side portions terminating in hooks adapted to engage with said trolley hook and said load-lowering chain respectively.

10. In a transfer apparatus for railway ties, a transfer device for shifting a tie-carrier between a trolley hook and a load-lowering chain consisting of a substantially triangular member having a base portion on which the tie-carrier is slidably suspended and upwardly and inwardly inclined side portions terminating in hooks adapted to alternately engage with said trolley hook and said load-lowering chain respectively, and a handle continuous with one of the hooks of said transfer device by which the latter may be tilted during the transfer operation.

ROBERT S. HURLEY.
